United States Patent Office

Des. 179,185

Patented Nov. 13, 1956

179,185

BUILDING BLOCK

Martin Branham, Pound, Va.

Application May 11, 1956, Serial No. 41,451

Term of patent 14 years

(Cl. D18—2)

Figure 1 is a perspective view of a building block showing my new design.

Figure 2 is an end elevational view of the same.

I claim:

The ornamental design of a building block, as shown.
